UNITED STATES PATENT OFFICE

2,366,590

SPEEDBOAT AND HULL

Henry Lowe Brownback, Norristown, Pa.

Application September 13, 1943, Serial No. 502,190

20 Claims. (CL. 114—66.5)

This invention is a novel improvement in speed boats and hulls, particularly of the hollow V or concave bow type, and the principal object of the invention is to provide a boat of the above type in which the keel line is disposed above the chine for approximately $\frac{2}{3}$ of the length of the boat, at which point the keel line passes below the chine line and runs aft below said chine line to the transom, the bottom of the hull aft of the point of intersection being of normal V type or of round bottom extending approximately $\frac{1}{3}$ the length of the boat from the rear, my novel design providing a more efficient hull than those heretofore designed, making the boat easier to handle and obviating the tendency in boats of the above general type from collecting floating debris and directing it into the line of the propeller or rudder.

Another object of the above invention is to provide a speed boat or hull of the above type which may be driven either by a water propeller or by an air propeller.

Another object of the invention is to provide a speed boat and hull of the above type in which the boat is of general rectangular plan with sections of either a hollow V or concave form at the bow, these sections becoming gradually flatter as they approach the stern, until at approximately $\frac{2}{3}$ the distance from the bow to the stern they become flat, and then assume a positive V, or a convex shape extending aft to the stern; my design providing a speed boat or hull in which the wave and air collecting qualities of the hollow V or concave bottom are preserved, the boat riding upon a cushion of air and water at all times, the cushion continuing under the hull under the positive V or convex stern until it escapes under the transom; hence, in case of a turn or a skid the positive convex V stern section causes the boat to bank inwardly and thus be stable as distinguished from the action of speed boats having hollow V sections extending completely to the transom, which even though relieved by so-called skid chines tend to trip and under severe conditions to overturn, this being particularly true where the center of gravity of the hull and/or superstructure and machinery produce a high center of gravity in the entire boat, and therefore increases the tendency of the boat to become unstable under unfavorable conditions.

Other minor objects of the invention will be hereinafter set forth.

I will explain the invention with reference to the accompanying drawings, which illustrate several practical embodiments thereof to enable

others familiar with the art to adopt and use the same; and will summarize in the claims the novel features of construction, and novel combinations of parts, for which protection is desired.

5 In said drawings:

Fig. 1 is a side elevation, partly broken away, of a boat hull embodying my invention, indicating in dotted lines the floor line, keel line, and also indicating the chine line.

10 Fig. 2 is a top plan view of the starboard side of the boat hull shown in Fig. 1, with the floor planking removed to show the arrangement of framing under the floor.

Fig. 3 is an enlarged half section on the line 15 3—3, Fig. 1.

Fig. 4 is an enlarged half section on the line 4—4, Fig. 1.

Fig. 5 is an enlarged half section on the line 20 5—5, Fig. 1, at which point the keel line crosses the chine line.

Fig. 6 is an enlarged half section on the line 6—6, Fig. 1.

Fig. 7 is an elevation showing a typical floor beam.

25 Fig. 8 is a section on the line 8—8, Fig. 7.

Fig. 9 is a diagrammatic view showing the arrangement of engine and propeller in a water propelled hull, and also showing the arrangement of the rudder.

30 Fig. 10 is a view similar to Fig. 9 showing the arrangement of engine, propeller, and rudder, in an air propelled hull.

As shown in Fig. 2, the hull is preferably rectangular in plan consisting of opposite side plates 35 disposed at a slightly upward flare as disclosed in Figs. 3 to 6, said side plates being preferably but not necessarily formed of 5-ply approximately $\frac{1}{4}$ inch thick. Other materials, plies and thicknesses may be used varying with the size 40 of the boat.

The sheer line 1a and chine line 1b of the side plates 1 are preferably disposed slightly farther apart adjacent the bow than at the stern, giving the sheer line 1a a slight dead rise above the 45 chine line 1b at the bow of the boat, the chine line being rounded as at 1c at a point adjacent the bow and extending upwardly and forwardly to meet the sheer line at the bow. The rear ends of the side members 1 are connected by a transom 2, Figs. 1, 2 and 6, and substantially the same width is maintained throughout the length 50 of the hull.

The keel line 1d extends from a point at the bow somewhat slightly below the sheer line 1a (Fig. 1) and passes rearwardly and downwardly

in a curve of large radius to a point $1e$ disposed approximately $\frac{1}{3}$ the length of the hull from the bow to the stern, at which point $1e$ the keel line $1d$ crosses the chine $1b$ and continues below the chine line to the transom 2 , as clearly indicated in Fig. 1.

The bottom of the hull from the bow to the point $1e$ of the keel line is of the type known as the hollow V or concave, the keel line $1d$ being disposed above the chine line $1b$. The bottom of the hull aft of the point $1e$ of keel line $1d$ is of normal V or round bottom extending aft approximately $\frac{1}{3}$ of the length of the boat, the shape of the bottom, fore and aft of the point $1e$, being clearly indicated in Figs. 3, 4, 5 and 6 of the drawings.

Fig. 3 shows a section of the boat through the hull taken at the line 3-3, Fig. 1. At this point the hollow V or concave section is relatively deep, while Fig. 4 shows the hollow V or concave becoming flatter at the section 4-4, Fig. 1, the depth of the hollow V or concave section varying in accordance with the spacing between the keel line $1d$ and chine line $1b$ in Fig. 1. Fig. 5 shows a section at the point where the keel line $1d$ crosses the chine line $1b$, the same being taken at section 5-5, Fig. 1, i. e., point $1e$ of the keel line. At this section the bottom of the hull is flat, the keel line being at the same distance from the base line as the chine line $1b$. In Fig. 6 the keel line $1d$ being disposed below the chine line $1b$ adjacent the stern of the boat and Fig. 6 shows the bottom at this point being a normal V or rounded bottom.

By such construction of the bottom of the hull, the wave and air collecting quantities of the hollow V bottom are preserved, the boat riding on a cushion of air and water at all times, the cushion continuing under the hull even below the positive V convex bottom shown in Fig. 6 until the cushion escapes under the transom 2 . In case of a turn or a skid the positive convex or V type stern will cause the boat to bank inwardly and thus be stable. In the type of boats heretofore constructed however in which the hollow V section extends completely abaft to the transom, even though relieved by so-called skid chines, tend to trip and under severe conditions to overturn. This is particularly true where the center of gravity of the boat hull and/or superstructure and machinery produces a high center of gravity of the boat, and therefore presents a greater tendency to become unstable under unfavorable conditions. The positive V or convex bottom adjacent the stern tends moreover to free the water propeller and rudder from debris which may be directed into it by the hollow V or concave sections forward of the point $1e$ of keel line $1d$.

As shown, the floor line $1f$ (Fig. 1) of the boat is disposed above the keel line $1d$ and is substantially parallel with the chine line $1b$ for substantially the rear half of the length of the hull, but gradually rises from such point to meet the sheer line $1a$ at the bow of the boat. The floor 3 is preferably but not necessarily of 5-ply approximately $\frac{3}{8}$ inch thick, and is disposed horizontally of the hull along the floor line $1f$, the same gradually rising from a point adjacent the center of the boat to meet the sheer line $1a$ at the bow of the boat, while the bottom 4 of the hull is preferably but not necessarily 5-ply approximately $\frac{1}{4}$ inch thick and is of curvature to conform with the keel line and chine line as indicated in Fig. 1 and in Figs. 3 to 6 inclusive.

Between the keel line $1d$ and floor line $1f$, dis-

posed axially of the boat, is a keel 5 which varies in depth according to the distance between the floor line $1f$ and keel line $1d$, the keel 5 preferably but not necessarily being formed of 5-ply approximately $\frac{1}{4}$ inch thick having its upper edge secured to a longitudinal member $5a$ disposed under the floor plate 3 and its lower edge secured to a longitudinal member $5b$ disposed above the bottom plate 4 of the hull, the parts $5, 5a$ and $5b$ being securely held together in any desired manner.

The framing of the hull forms no part of my present invention, and may consist of normal transverse framing or may consist of diagonal framing as shown in Figs. 2 and 6; but same may be of any other desired type. Fig. 2 shows a plan view of the diagonal framing at the starboard side of the hull, floor plate 3 being removed. The frames 6 adjacent the bow of the boat may be constructed as shown in Figs. 2 and 6, the same consisting of a member $6a$ disposed under the floor 3 and extending from the keel 5 to the side plate 1 , a similar member $6b$ extending from the keel to the chine line $1b$ above the bottom plate 4 of the hull, which members may be reinforced by vertical members $6c$ (Fig. 2) at desired intervals. A web $6d$ preferably but not necessarily of 5-ply approximately $\frac{1}{4}$ inch thick is secured to the members $6a$ and $6b$ as shown in Fig. 3. Preferably a stringer $3a$ is provided along the side 1 under the outer edges of the floor 3 . Preferably the alternate remaining frames 7 are constructed in a manner similar to the frames 6 above described. The intermediate remaining floor frames 8 are preferably constructed as shown in Figs. 7 and 8, the same consisting of upper members $8a$ and lower members $8b$ conforming with the undersurface of the floor 3 and upper surface of the bottom 4 of the hull respectively in the same manner as above described in connection with members $6a$ and $6b$ of floor frames 6 . Instead however of having a continuous web plate $6d$ extending between the members $8a, 8b$, substantially T-shaped gusset plates $8d$, Figs. 7 and 8, are disposed opposite the vertical members $8c$, the same being disposed at opposite faces of the floor frames 8 so as to reduce weight. Any other desired form of framing however may be used, transverse, diagonal, or longitudinal. Also preferably the sides 1 may be further reinforced by frame members 10 , Figs. 1, 2 and 5, passing through the floor 3 and terminating at the bottom 4 of the hull.

At the sheer line $1a$ is a hand grip 9 , the same continuing across the upper edge of the transom 2 and across the bow of the boat. Preferably angle irons 11 extend along the chine line $1b$ the same terminating at a point adjacent the bend $1c$ of said line where the angle iron 11 is replaced at the bow by a rub strake 12 , Fig. 1, for the purpose of protecting the front end of the chines.

Fig. 9 shows the hull equipped with a water propeller 13 mounted upon a shaft 14 extending through a boss 15 projecting below the keel line $1d$ adjacent the stern of the boat and through an inside stuffing box, the shaft 14 being driven by a motor 16 of the internal combustion or any other type; a rudder 17 being applied to the rear end of the hull opposite the keel. In this construction the positive V bottom or convex bottom 4 of the hull adjacent the stern will tend to free the propeller 13 and rudder 17 from debris which may be directed thereagainst by the hollow V section of the hull disposed in advance of the positive portion, i. e., forward of the point $1e$, Fig. 1,

Fig. 10 shows a hull equipped with an air propeller 19 driven by motor 18 and disposed adjacent the stern of the hull. When using an air propeller as shown in Fig. 10 the hull per se may be further designed in accordance with my Letters Patent No. 1,686,264 dated October 2, 1928, so that the boat upon attaining sufficient speed will be supported on the surface of the water through dynamic reaction upon its bottom surface, the hull of the boat and its aerial propeller being so arranged that the center of lift of the bottom surface of the hull, and the center of resistance of the hull is forward and below the center of gravity of the boat, while the center of thrust of the aerial propeller is above and to the rear of the center of gravity, so that any derangement of the balance of forces sustaining, retarding and propelling the boat will tend to raise the boat at the center of gravity, and any substantial increase in the application of propelling power or any combination of external forces which may tend to raise the stern or depress the bow suddenly will tend to move the center of lift and the center of resistance forward, the center of gravity being of course stationary, and thereby restore the stability of the hull; or these remaining stationary, to revolve the boat about the resultant force, thus attempting to lift the boat at its center of gravity and depressing the bow, moving the center of resistance forward and restoring the equilibrium of forces acting on the hull.

When using either the water or air propellers however, the design of the hull which is roughly rectangular in plan with sections of either a hollow V or concave form at the bow, these sections become readily flatter as they approach the stern, until at approximately $\frac{2}{3}$ the distance from the bow to the stern they become flat and then assume a positive V or a convex form at the stern, the wave and air collecting qualities of the hollow V bottom are preserved causing the boat to ride upon a cushion of air and water at all times, the cushion continuing under the hull even with the positive V convex form aft until it escapes under the transom. In case of a turn or skid the positive V type stern sections will cause the boat to bank inwardly and thus be stable. Ordinarily, boats having hollow sections which continue completely to the transom, even when relieved by so-called skid chines, tend to trip and under severe conditions overturn, this being particularly true where the center of gravity of the hull and/or superstructure and machinery cause a high center of gravity of the entire boat, and therefore produce a greater tendency to become unstable under unfavorable conditions.

I do not limit my invention to the exact forms shown in the drawings, for obviously changes may be made therein within the scope of the claims.

I claim:

1. A hull for speed boats, comprising substantially parallel sides, a transom, a bottom; the lower edges of the sides defining chine lines and the upper edges of the sides defining the sheer line; said sheer line and chine line being for the major portion of their lengths substantially parallel; an axially disposed keel disposed upon the bottom, the lower edge of the keel defining the keel line; and said keel line extending from a point adjacent the sheer line at the bow and passing below the chine line at a point approximately two-thirds the length of the hull from the bow and continuing below the chine line from said passing point to the transom, whereby the hull will have a hollow V bottom from the bow gradually

diminishing in depth to the passing point where the bottom is flat, and will have a convex V bottom from said passing point gradually increasing in depth to the transom.

6. 2. In a hull as set forth in claim 1, said sides being upwardly flaring.
3. In a hull as set forth in claim 1, said sheer line being further spaced from the chine line adjacent the bow, to impart a dead-rise to the sheer line.
4. A hull for speed boats of substantially rectangular plan, comprising sides, a transom, and a bottom; the lower edges of the sides defining the chine lines rounded upwardly at the bow to meet the sheer line defined by the upper edges of the sides; a floor within said hull; an axially disposed keel disposed between the floor and bottom, the lower edge of the keel defining the keel line; and said keel line extending from a point adjacent the sheer line at the bow and passing below the chine line at a point approximately two-thirds the length of the hull from the bow and continuing below the chine line from said passing point to the transom, whereby the hull will have a hollow V bottom from the bow gradually diminishing in depth to the passing point where the bottom is flat, and will have a convex V bottom from said passing point gradually increasing in depth to the transom.
5. In a hull as set forth in claim 4, said sides being upwardly flaring.
6. In a hull as set forth in claim 4, said floor being substantially parallel with the chine line for substantially the aft half of the hull.
7. In a hull as set forth in claim 4, said sheer line adjacent the bow being further spaced from the chine line to impart a dead-rise to the sheer line.
8. A hull for speed boats of substantially rectangular plan, comprising sides, a transom, and a bottom; the lower edges of the sides defining the chine lines rounded upwardly at the bow to meet the sheer line defined by the upper edges of the sides; a floor within said hull extending from the transom and sloping upwardly to meet the sheer line at the bow; an axially disposed keel disposed between the floor and bottom, the lower edge of the keel defining the keel line; said keel line extending from a point adjacent the sheer line at the bow and passing below the chine line at a point approximately two-thirds the length of the hull from the bow and continuing below the chine line from said passing point to the transom, whereby the hull will have a hollow V bottom from the bow gradually diminishing in depth to the passing point where the bottom is flat, and will have a convex V bottom from said passing point gradually increasing in depth to the transom.
9. In a hull as set forth in claim 8, said sides being upwardly flaring.
10. In a hull as set forth in claim 8, said floor being substantially parallel with the chine line for substantially the aft half of the hull.
11. In a hull as set forth in claim 8, said sheer line adjacent the bow being further spaced from chine line to impart a dead-rise to the sheer line.
12. A hull for speed boats of substantially rectangular plan, comprising sides, a transom, and a bottom; the lower edges of the sides defining the chine lines rounded upwardly at the bow to meet the sheer line defined by the upper edges of the sides; a floor within said hull extending from the transom and sloping upwardly to

meet the sheer line at the bow; an axially disposed keel disposed between the floor and bottom, the lower edge of the keel defining the keel line; said keel line extending from a point adjacent the sheer line at the bow and passing below the chine line at a point approximately two-thirds the length of the hull from the bow and continuing below the chine line from said passing point to the transom, whereby the hull will have a hollow V bottom from the bow gradually diminishing in depth to the passing point where the bottom is flat, and will have a convex V bottom from said passing point gradually increasing in depth to the transom; and framing within the hull disposed between the floor and bottom and extending from the keel to the sides and transom.

13. In a hull as set forth in claim 12, said sides being upwardly flaring.

14. In a hull as set forth in claim 12, said floor being substantially parallel with the chine line for substantially the aft half of the hull.

15. In a hull as set forth in claim 12, said sheer line adjacent the bow being further spaced from the chine line to impart a dead-rise to the sheer line.

16. A speed boat comprising a hull of substantially rectangular plan, including sides, a transom, and a bottom, the lower edges of the sides defining the chine lines rounded upwardly at the bow to meet the sheer line defined by the upper edges of the sides; a floor within said hull extending from the transom and sloping upward-

ly to meet the sheer line at the bow; an axially disposed keel disposed between the floor and bottom, the lower edge of the keel defining the keel line; said keel line extending from a point adjacent the sheer line at the bow and passing below the chine line at a point approximately two-thirds the length of the hull from the bow and continuing below the chine line from said passing point to the transom, whereby the hull will have a hollow V bottom from the bow gradually diminishing in depth to the passing point where the bottom is flat, and will have a convex V bottom from said passing point gradually increasing in depth to the transom; framing within the hull between the floor and bottom extending from the keel to the sides and transom; a propeller; and an engine for driving said propeller.

17. In a boat as set forth in claim 16, said sides being upwardly flaring.

18. In a boat as set forth in claim 16, said sheer line adjacent the bow being further spaced from the chine line to impart a dead-rise to the sheer line.

19. In a boat as set forth in claim 16, said propeller being mounted on a shaft extending downwardly and rearwardly through the keel aft of the passing point, and being disposed below the convex V bottom adjacent the stern.

20. In a boat as set forth in claim 16, said propeller being disposed above the hull at a point adjacent the stern.

HENRY LOWE BROWNBACK.
